UNITED STATES PATENT OFFICE.

ALFRED COLLIS AND JOHN HENRY COLLIS, OF LONDON, ENGLAND.

CUTTING-MACHINE FOR PAPER.

1,118,843.

Specification of Letters Patent.

Patented Nov. 24, 1914.

Application filed November 21, 1912. Serial No. 732,743.

To all whom it may concern:

Be it known that we, ALFRED COLLIS and JOHN HENRY COLLIS, subjects of the King of Great Britain, residing at London, England, have invented certain new and useful Improvements in or Connected with Cutting-Machines for Paper and the like, of which the following is a specification.

The object of our invention is to improve the construction of that type of machines for cutting paper and the like from the web in which the latter is severed in a direction transverse to its motion by means of a revolving knife in such a manner that all the sheets shall be cut true, square and to size.

The improvements proposed by the invention consist principally of a revolving knife and a fixed or dead knife which travel along at the same speed as the paper web, and a clamping appliance, or appliances, which holds or steadies the paper while the cutting is taking place. We also include mechanism for determining the length of the sheet to be cut, before starting up the machine, as is now the usual practice.

Our invention is not confined to square cutting machines, as it can be applied to angle or duplex cutting machines; that is to say, a machine that cuts two different size sheets side by side. It could also be applied to any cutting machine of the types referred to, however many different size sheets are cut. In cutting machines of this type of the kind wherein sheets of paper are cut from the web or reels, a great deal of trouble and waste of paper have hitherto been caused by the revolving knife not cutting the sheets true and square and to one size; also, a large amount of paper has to be wasted and considerable time expended in starting to cut a fresh set of sheets. This has been brought about by the cutting knives acting with a scissor-like motion, and as the web of paper is of a considerable width, some even being as

wide as 150 inches, the knife in revolving severs the sheets at one side of the web considerably in advance of the other side, as the knife is set to cut in this way. Therefore, the knives have to be set in relation to the paper in such a way as to allow for the time lost by the knife cutting one side sooner than the other. As this timing is usually done by guesswork, considerable time is lost before it is satisfactorily completed. With our machine, these difficulties are obviated by making the revolving knife and dead

knife sever the paper while they are moving at the same speed at which the paper is traveling.

In the ordinary way, one or more reels of paper is placed in a reel frame behind the cutter and fed between rollers over the fixed knife, (sometimes known as the dead knife). The revolving knife acting against the fixed or dead knife severs the sheet, or sheets, which is, or are, then carried away, and either laid automatically on a receiving appliance such as shown in Patent No. 973,259, dated October 18, 1910, or by hand. This revolving knife is varied in speed in relation to the speed of the paper, so as to cut the sheets the desired length. In former machines of this type, the dead knife has always been stationary; that is to say, it does not move in any direction. According to our invention, however, the dead knife is only fixed in relation to the revolving knife, as both knives are connected together or mounted on a carriage which receives a reciprocating motion, and the forward movement of the carriage is so timed that the clamp acts on the paper as it moves forward, the clamp holding the paper while it is severed by the revolving knife. This severance takes place while the paper is traveling forward with the dead knife.

It will be seen that as the carriage travels forward at the same rate of speed as and with the paper, the dead knife and paper do not alter their relative position one to the other during the cut, although the knives have a scissor's-like action and are cutting for some perceptible time, and in consequence the sheet or sheets can be cut square and true with the sides of the web. Also, mechanism is provided for determining the length of the sheet to be cut, by varying the speed at which the cutting knife revolves in relation to the rollers which draw the paper into the cutting machine.

An embodiment of the invention is illustrated in the annexed drawing, wherein:

Figure 1 is a side elevation of the improved cutting machine; Fig. 2 is a part-sectional, fragmental plan view thereof; Fig. 3 is a detail plan view of the mechanism for determining the length of the sheets to be cut; Fig. 4 is a side elevation of the knife carriage; Fig. 5 is an enlarged horizontal sectional view of the friction clutch; Figs. 6 and 7 are, respectively, a part-sectional plan view and a front elevation of an alter-

native form of length-determining mechanism; and Fig. 8 is a diagrammatic side elevation of the mechanism for driving the cutting machine.

Referring to said drawing, 1 indicates, generally, the frame of the cutting machine, and 2 the reciprocating knife carriage which is mounted upon the top of said frame and travels upon rollers 35. The carriage may be actuated by means of any desired mechanism, and in the present instance it is depicted as connected at each side by a rod 4 to a horizontal rack 3, also mounted in said frame, but since only one side of the machine appears in Fig. 2, it will be obvious that one rack and rod alone are illustrated. These racks are shifted in one direction, (forwardly), by means of pinions 5 which are in mesh therewith and are mounted on a cross-shaft 67, and that shaft is driven from a pulley 97 on the main shaft 80, (Fig. 8), through the agency of suitable connecting devices. The devices just referred to, are here shown as embodying a belt 98 which connects pulley 97 with a pulley 100 fast on a cross-shaft 101, a gear 102 on the latter shaft in mesh with and driving a large gear 103 fast on a third cross-shaft 104, and a gear 6 loosely mounted on shaft 104 and meshing with the adjacent gear 5, the loose gear 6 being driven by means of a clutch mechanism hereinafter described. The several shafts 80, 101, 104 and 67 are suitably journaled in horizontal position in the frame, and the first-named or drive shaft carries a pulley 81 which is connected with the main source of power, the belt 98 connecting said shaft and the shaft 101 being trained over guide pulleys 99.

The afore-mentioned clutch mechanism, which serves to render the loose gear 6 operative, is preferably constituted by a male member or sleeve 7 that is splined on shaft 104 and is shifted into and out of frictional engagement with the internal clutch surface provided in said gear. (Figs. 2 and 5). To effect this shifting of the clutch sleeve, there is utilized in the present construction a fork 8 which is centrally pivoted to a bracket 53 on the frame, the terminals of the arms of the fork being attached to bushings or sleeves 9. These sleeves 9 are slideable relatively to a pair of rods 11 that are fastened at their inner ends to a strap 12, which fits in a groove in the clutch sleeve 7, the outer ends of the rods being provided with heads for co-operation with the enlarged outer portions of the sleeves 9. The reduced inner portions of the latter sleeves fit slidably in openings in the adjacent frame member and are likewise provided with terminal heads. The rocking movement of fork 8 is effected by means of a cam 13 which engages the lower end of the fork, (Fig. 1), and this cam is mounted on a horizontal

shaft 90, (Fig. 8), that is rotated from the drive shaft in the following manner. Shaft 80 has splined thereto a pulley 38 which is connected by a belt 82 with a similar pulley 39 splined on a shaft 83, so as to rotate the latter, the pulleys 38 and 39 having certain particular structural features which will be hereinafter set forth. Shaft 83 carries a sprocket 84 that is connected by a chain 85 with a sprocket 86 fast on a shaft 87, this shaft 87 also carrying a gear 88 in mesh with a gear 89 which is mounted on the opposite end of shaft 90 from cam 13. In consequence of this arrangement, the rotation of said cam will cause a rocking movement of fork 8 and an attendant shifting of the clutch sleeve 7 in one direction, (i. e., into operative engagement with the friction surface in gear 6). When this takes place, shaft 104 will be rotated until the fork terminal reaches the lower part of the cam, whereupon the clutch 7 will be forced out of engagement with gear 6 through the agency of a pair of springs 10 that encircle the rods 11 and are interposed between the strap 12 and the headed inner ends of the sleeves 9. Accordingly, it will be apparent that during the forward movement of the racks, the knife carriage 2 will have a corresponding movement imparted thereto.

The return or rearward movement of the carriage is effected automatically by the action of springs 33, (Figs. 1, 2 and 4), which are themselves tensioned when the carriage moves forwardly. At each side of the frame, at the top thereof, is arranged a horizontal guide rod 31 which extends loosely through a longitudinal passage or recess in the adjacent side member of the carriage and is encircled by one of the said springs 33. These rods are anchored at their rear ends to stops 37^a mounted on the frame, and each is provided with a collar 32 against which bears the adjacent end of the spring carried thereby, the front end of the spring bearing against a stop or shoulder 34 in the afore-mentioned passage or recess. This arrangement produces, therefore, a compression of the springs when the carriage is moved in the direction indicated, the expansion of the springs consequent upon the release of the clutch returning said carriage until its rear end abuts against the slots 37^a, as depicted in Fig. 2. The forward movement of the carriage is similarly limited by a pair, or pairs, of coacting stops 36 and 37, the former being adjustably mounted on the frame, (Fig. 1), and the latter attached to the front member of the carriage.

The knives 27^a and 27 are mounted on the carriage, the first of these knives being fixed and constituting the so-called "dead" knife. The knife 27 revolves about a shaft 96, (Fig. 8), mounted in said carriage, and is, in the main, of conventional type. The knife shaft

96 is driven from the pulley shaft 83, hereinabove referred to, through the intermedia-
tion of gearing here shown as constituting
of a substantially vertical shaft 93 which
5 is provided at its opposite ends with bevel
gears 92 and 94 that mesh, respectively,
with similar gears 91 and 95, carried by
the said knife and pulley shafts. Pro-
vision is made for an oscillating or swing-
10 ing movement of shaft 93, owing to the
mounting of the knife shaft 96 in the re-
ciprocating carriage 2, and this may be ac-
complished in any desired manner, as, for
instance, by connecting the upper and lower
15 bearings for said shaft 93 to the knife and
pulley shafts 96 and 83, respectively, but
since the mounting in question forms no
part of the invention, illustration thereof
is considered unnecessary, especially as such
20 illustration would obscure the drawing.

The paper web 63 is led to the cutting ma-
chine from any suitable source of supply,
and is passed around guide rollers 58 and
59, (Fig. 1), and thence between the draw-
ing or feed rollers 14 and 15, the lower roller
25 14 being mounted upon the clutch shaft 104.
After leaving these rollers, the web passes
successively along the incline 16, between the
pair of slitting knives 17 and 18, (which
30 cut it longitudinally), along a second in-
cline 62 and between the pair of nipping
rollers 19 and 20, the latter rollers, in turn,
feeding the web beneath a clamp 22, ar-
ranged at the front end of the carriage, and
35 over the dead knife 27^a to the revolving
knife 27. The sheets cut by said knives pass
down a second incline 28 onto a felt 29, and
are delivered by the felt to the laying mech-
anism, (not shown) which latter may be of
40 the type shown and described in Patent No.
973,259, bearing date of October 18, 1910, or
of any other desired construction. The felt
passes around rollers 66 and 69, over guide
rollers 68, and under a take-up roller 67^a,
45 the roller 69 being driven by or from the
laying mechanism, and during their travel
along the upper stretch of said felt, the
sheets pass beneath a roller 30 which bears
upon said stretch, and is mounted at the
50 lower end of a pivotally-mounted rod 30^a
connected to the carriage 2. The sheets are
supported between the nipping rollers 19
and 20, and the carriage by means of a se-
ries of bands 21, which may be made of
55 steel, tape or other suitable material, the
bands being fastened at one end to the in-
cline 62 and at the other end to a transverse
shaft 65 mounted in the frame 1. Beyond
the nipping rollers, the bands pass around
60 rollers 64 and 54, the roller 64 being mount-
ed on the front end of the carriage directly
in advance of clamp 2, while the roller 54,
which is grooved at intervals to receive said
bands, is mounted at its ends in bearings 55,
65 (Fig. 2), provided upon the outer ends of a

pair of rods 56 that work in openings
formed in opposite sides of the carriage.
Said rods are normally held in projected
position by encircling coilsprings 57, where-
by the roller 54 is kept pressed against the 70
bands 21, so as to maintain the same taut
during the movements of the carriage. The
lower nipping roller 19 is also grooved, in
order to permit the said bands to lie below
its peripheral surface, thereby preventing 75
the bands from interfering with the requi-
site drawing action of the rollers.

In the construction illustrated, the afore-
mentioned clamp 22 has the form of a bar,
which is disposed transversely of the car-
riage, at the front thereof, and is raised or
lowered by means of a pair of depending
rods 23 connected to its ends, only one of
such rods appearing, however, owing to the
fragmentary character of Fig. 2. The rods 85
23 are actuated by means of bell-crank le-
vers 24 that are pivoted upon studs 25 fixed
on the carriage and are provided upon the
free ends of their rear arms with rollers 25^a
engaged with cams 26 fixed upon the knife 90
shaft 96. These cams obviously rotate at
the same speed as the knife 27, and, hence,
any variation in the speed of the latter will
correspondingly affect the timing of the
operation of the clamp. 95

It is proposed to vary the speed at which
the knife 27 revolves, in order to regulate
the length of the sheets to be cut, and this
variation is accomplished primarily through
the agency of the pulleys 38 and 39, owing 100
to the gearing connecting the knife shaft
96 with the shaft 83 whereon pulley 39 is
mounted. Both pulleys are of the so-called
“expansion” type and are composed of op-
positely-disposed, frusto-conical disks, (Fig.
105 3), which are slidable toward and from each
other on their respective shafts, the belt 82
which connects said pulleys having a sub-
stantially triangular cross-sectional shape,
as will be understood. 110

To effect the above-specified movements of
the pulley sections or members, there is
preferably provided a pair of levers 42 and
43 which are disposed upon opposite sides
of said pulleys, and are loosely connected 115
with the hubs of said sections. These levers
are fulcrumed intermediate their ends, upon
a pair of collars 44 and 45 carried by a shaft
or rod 40 that is arranged between and par-
allel with the pulley shafts 80 and 83, and
at their front ends said levers have a loose
connection with a pair of traveling nuts 47
and 46 that work on the right- and left-
hand threads formed on a screw-shaft 41 ar-
ranged parallel with and in front of shaft
80. In consequence, rotation of shaft 41 will
produce a movement of the nuts 47 and 46
either toward or from each other, according
to the direction of such rotation, with the
results that the levers 42 and 43 impart a 125
130

- corresponding movement to the sections of pulley 38 and a reverse movement to those of the pulley 39, owing to the fulcra of said levers being located between said pulleys.
- 5 The collars 44 and 45 are preferably threaded on their rod or shaft 40, and are thus rendered adjustable for the purpose of taking up slack in belt 82, or of compensating for wear.
- 10 To rotate the screw-shaft 41, either the mechanism shown in Figs. 1 and 3 or that shown in Figs. 6 and 7 may be employed, or, in fact, any other mechanism of a like character. In the former construction, the 15 screw-shaft carries a hand wheel 52 and, also a worm 48 which latter meshes with and drives a worm wheel 49 whose shaft is supported in a journal bracket 50 attached to the frame. The face of the worm wheel has secured thereto a graduated disk 51 with which a vernier 51^a co-operates, the vernier being marked with graduations to indicate the various lengths of the sheets to be cut, and when a desired mark on the disk 51 20 alines with one of the divisions of the vernier, the length of the sheets cut will be that indicated by such division, as will be apparent.
- In the alternative construction depicted 25 in Figs. 6 and 7, the screw-shaft is provided with a bevel gear 70 that meshes with and drives a similar gear 71 on the lower end of a vertical shaft 72. The latter shaft is journaled in bearings 78 and 79 attached to the frame, and carries at its upper end a worm 35 73 which drives a worm wheel 74 mounted on a spindle 75. This spindle also carries a graduated wheel or disk 76, with which the vernier 77 coacts, the operation being the same as before and requiring only a few 40 seconds, whereas in the ordinary way much time is consumed in changing gears and pulleys.
- The operation is believed to be apparent, 45 in the main, from the foregoing, but it may be stated that as soon as the desired length of paper has been fed through, the clamp 22 is allowed to drop, owing to the rollers 25^a reaching the low part of the cams 26 at that time. The clamp operates to grip the paper 50 against a knife-beam just behind the dead knife 27^a, the paper being thus held and steadied when the revolving knife 27 commences to cut. At the same time, the clutch 55 sleeve 7 engages the gear 6, the latter being rotated thereby, with the result that the carriage is forced forward by the movement of the racks 3 which is caused by the rotation of the gears 5, and since this movement of 60 the carriage takes place at the same speed as the paper, the sheets will be cut true, and to the required size and shape.
- We claim:
1. In a sheet-cutting machine, the combination, with a frame; of a traveling carriage
- 65 mounted on said frame; cutting mechanism mounted in said carriage and comprising a fixed knife, and a revolving knife co-operating with the fixed knife but free of connection therewith; and mechanism for feeding the web and advancing said carriage at the same speed.
2. In a sheet-cutting machine, the combination, with a frame; of a traveling carriage mounted on said frame; a dead knife fixed in said carriage; a revolving knife mounted in said carriage for co-operation with the dead knife, but free of connection therewith, said revolving knife having its axis arranged transverse to the direction of movement of the web; means for operating said revolving knife; and mechanism for feeding the web and advancing said carriage at the same speed.
3. In a sheet-cutting machine, the combination, with a frame; of a traveling carriage mounted on said frame; a dead knife fixed in said carriage; a revolving knife mounted in said carriage for co-operation with the dead knife, but free of connection therewith, said revolving knife having its axis arranged transverse to the direction of movement of the web; means for operating said revolving knife; a clamp mounted on said carriage for holding and steadyng the web during the cutting operation; and mechanism for feeding the web and advancing said carriage at the same speed.
4. In a sheet-cutting machine, the combination, with a frame; of a traveling carriage mounted on said frame; a dead knife fixed in said carriage; a revolving knife mounted in said carriage for co-operation with the dead knife, but free of connection therewith, said revolving knife having its axis arranged transverse to the direction of movement of the web; means for operating said revolving knife; a clamp operatively connected with said knife-operating means for holding and steadyng the web during the cutting operation; and mechanism for feeding the web and advancing said carriage at the same speed.
5. In a sheet-cutting machine, the combination, with a frame; of a traveling carriage mounted on said frame; cutting mechanism mounted on said frame; cutting mechanism mounted in said carriage; cutting mechanism and a clamp mounted in said carriage, said cutting mechanism including a revoluble cutter; mechanism for feeding the web and simultaneously moving said carriage in one direction at the same speed; means for operating said cutter during such movement; and means for automatically returning said carriage at the conclusion of the cutting operation.
6. In a sheet-cutting machine, the combination, with a frame; of a traveling carriage mounted on said frame; cutting mechanism

130

and a clamp mounted in said carriage, said cutting mechanism including a revoluble cutter; mechanism for feeding the web and simultaneously moving said carriage in one direction at the same speed; means for operating said cutter during such movement; means for operating said clamp during the cutting operation, to hold and steady the web; and means for automatically returning said carriage at the conclusion of the cutting operation.

7. In a sheet-cutting machine, the combination, with web-feeding mechanism; of a cutting mechanism comprising a fixed knife, and a revoluble knife coöperating with the fixed knife, but free of connection therewith; and means for moving said cutting mechanism bodily in one direction at the same speed as the web.

20 8. In a sheet-cutting machine, the combination, with web-feeding mechanism; of a cutting mechanism comprising a fixed knife, and a revoluble knife coöperating with the fixed knife, but free of connection therewith; a clamp coöperating with said knives for holding and steadyng the web during the cutting operation; and means for moving said cutting mechanism and said clamp bodily in the direction in which the web is fed, and at the same speed as the web.

25 9. In a sheet-cutting machine, the combination, with web-feeding mechanism; of a cutting mechanism comprising a fixed knife, and a revoluble knife coöperating with the fixed knife, but free of connection therewith; means for moving said cutting mechanism bodily in one direction at the same speed as the web; means for operating the cutting mechanism during such movement; and 30 means for automatically returning said cutting mechanism to normal position at the conclusion of such movement.

10. In a sheet-cutting machine, the combination, with web-feeding mechanism, and 45 operating means therefor; of a cutting mechanism; and a rack-and-gear connection between the feeding and cutting mechanisms for moving the latter mechanism bodily in the direction in which the web is fed, and 50 at the same speed as the web.

11. In a sheet-cutting machine, the combination, with web-feeding mechanism, and operating means therefor including an automatically-actuated clutch; of a cutting 55 mechanism; and a rack-and-gear connection between the feeding and cutting mechanisms for moving the latter mechanism bodily in the direction in which the web is fed and at the same speed as the web.

60 12. In a sheet-cutting machine, the combination, with web-feeding mechanism; of a cutting mechanism comprising a fixed knife, and a revoluble knife coöperating with the fixed knife, but free of connection therewith; means for moving said cutting mech-

anism bodily in one direction at the same speed as the web; and variable-speed driving means connected with said revoluble knife for regulating the length of the sheets to be cut.

70 13. In a sheet-cutting machine, the combination, with web-feeding mechanism and operating means therefor; of a cutting mechanism including a revoluble cutter; means for moving the cutting mechanism bodily in the same direction and at the same speed as the web; variable-speed driving means connected with said revoluble cutter for regulating the length of the sheets to be cut; and an indicating mechanism operatively associated 75 with said driving means for controlling the speed thereof.

14. In a sheet-cutting machine, the combination, with web-feeding mechanism and operating means therefor; of a cutting mechanism; and variable-speed driving means connected with said cutting mechanism for regulating the length of the sheets to be cut, said driving means embodying a pair of expandible pulleys, a belt connecting the same, 80 and means connected with said pulleys for controlling their expansion.

85 15. In a sheet-cutting machine, the combination, with web-feeding mechanism and operating means therefor; of a cutting mechanism; and variable-speed driving means connected with said cutting mechanism for regulating the length of the sheets to be cut, said driving means embodying a pair of expandible pulleys, a belt connecting the same, 90 and a pair of levers connected to said pulleys and arranged on opposite sides thereof for controlling their expansion.

95 16. In a sheet-cutting machine, the combination, with web-feeding mechanism and operating means therefor; of a cutting mechanism; and variable-speed driving means connected with said cutting mechanism for regulating the length of the sheets to be cut, said driving means embodying a pair of expandible pulleys, a belt connecting the same, 100 a pair of levers connected to said pulleys and arranged on opposite sides thereof for controlling their expansion, and means for operating said levers in unison.

110 17. In a sheet-cutting machine, the combination, with web-feeding mechanism and operating means therefor; of a cutting mechanism; variable-speed driving means connected with said cutting mechanism for regulating the length of the sheets to be cut, said driving means embodying a pair of expandible pulleys, a belt connecting the same, and means connected with said pulleys for controlling their expansion; and an indicating mechanism operatively associated with 115 said controlling means.

120 18. In a sheet-cutting machine, the combination, with web-feeding mechanism and operating means therefor; of a cutting mecha-

- nism; and variable-speed driving means connected with said cutting mechanism for regulating the length of the sheets to be cut, said driving means embodying a pair of expandable pulleys, a belt connecting the same, a pair of levers connected to said pulleys and arranged on opposite sides thereof for controlling their expansion, said levers being fulcrumed intermediate their ends and between said pulleys; and an operating shaft for said levers provided with right and left-hand screw threads with which the levers are engaged at one end.
19. In a sheet-cutting machine, the combination, with web-feeding mechanism and operating means therefor; of a cutting mechanism; and variable-speed driving means connected with said cutting mechanism for regulating the length of the sheets to be cut, said driving means embodying a pair of expandable pulleys, a belt connecting the same, a pair of levers connected to said pulleys and arranged on opposite sides thereof for controlling their expansion, said levers being fulcrumed intermediate their ends and between said pulleys; an operating shaft for said levers provided with right and left-hand screw threads with which the levers are engaged at one end; and an indicating mechanism operatively associated with said shaft.
20. In a sheet-cutting machine, the combination, with web-feeding mechanism, and operating means therefor, including an automatically actuated clutch; of a cutting mechanism, a pair of racks connected to the cutting mechanism; and gear connections between said racks and said feeding means for moving said cutting mechanism bodily in the same direction and at the same speed as the web when said clutch is operated.
21. In a sheet-cutting machine, the combination, with web-feeding mechanism, and operating means therefor, including an automatically operated clutch comprising fast and loose members the latter of which is provided with gear teeth; of a cutting mechanism; a shaft located adjacent the web-feeding mechanism and provided at each end with a gear, one of said gears meshing with the teeth on the clutch member; and a pair of racks in mesh with said gears and connected with said cutting mechanism for moving the latter bodily in the same direction and at the same speed as the web when said clutch is operated.

In testimony whereof we have hereunto set our hands in presence of two subscribing witnesses.

ALFRED COLLIS.
